CLOSURE APPLIANCE FOR BOTTLE CAPPING
MACHINERY

Thomas Leslie Goldsmith, London, England, assignor, by mesne assignments, to Clarke-Built Limited, London, England, a British company

Application February 23, 1951, Serial No. 212,286
In Great Britain February 23, 1950

2 Claims. (Cl. 226—85)

1

This invention relates to bottle capping and has particular reference to a closing appliance for securing over the mouth of a bottle a deformable cap, said closing appliance being of the kind in which a cap resting loosely over the mouth of a bottle is adapted to contact with a pressure element as said pressure element and/or the bottle move axially, for instance, relative to one another, such axial displacement being utilised to effect a contracting movement of lateral pressure means which act radially inwards to crush or crimp the depending wall of the cap around the lip of the bottle.

Moreover the improved appliance according to this invention relates to a type of the known kind of appliance, which type comprises a hollow housing, a pressure plunger axially displaceable within said housing and adapted to contact the crown of a deformable cap loosely seated over the mouth of a bottle and a plurality of rigid circumferentially-spaced arcuate sections which together constitute a contractible ring assembly adapted to encircle the neck of a bottle and the depending wall or skirt of the cap seated thereon when the bottle-supported cap is pressed against the pressure plunger, said ring sections and the surrounding housing having interacting tapering surfaces which on relative axial movement between said ring sections and said housing cause the ring sections to swing radially inward to deform the skirt of the bottle cap.

The object of the present invention is to provide an improved closing appliance of the type referred to, the improved appliance being especially adapted for securing preformed caps made of thin aluminum foil or similar readily deformable material over the mouths of milk and similar bottles.

The present invention provides a bottle cap securing appliance of the type referred to, which is characterised by the employment of a resilient bottle-cap skirt contacting element in the interior of the contractible ring assembly, so as to be interposed between the rigid ring sections and the thin foil of which the preformed cap is made. The use of such a resilient cap-contacting element, which is preferably in the form of a continuous ring of rubber or similar material, ensures uniform deformation of the thin-walled cap without the "bruising" of the foil which often occurs when rigid ring sections make direct contact with the foil.

The improved bottle cap securing appliance according to this invention also includes a further feature which assists in obtaining a smooth work-

2

ing action of the appliance, namely, that instead of pivotally attaching the sections of the contractible ring assembly to the pressure plunger, as has been done hitherto in appliances of this type, the ring sections are loosely supported for rocking on the pressure plunger in such a manner that as the radial contracting movement of the ring sections takes place the fulcrum points of said ring sections progressively change.

10 As a result, instead of a sudden contractive movement, a gradual squeezing action is obtained which is better adapted to the smooth closure of thin-walled foil caps. Another advantage accrues from the elimination of pivot pins for the ring sections, namely that the construction of the ring assembly is more robust, since the pivots as hitherto used have inevitably been of small size and thus subject to rapid and uneven wear. As a result, where pivoted ring sections are used, 15 excessive slackness may soon arise between the pivot pins and the associated ring sections and pressure plunger which tends to throw the ring sections out of alignment.

In order that the invention may be more readily 20 understood an embodiment thereof will now be described with the aid of the accompanying drawings, wherein:

Figure 1 is a vertical cross section through the 25 appliance,

Figure 2 is an inverted plan view, looking in 30 the direction of arrow II, Figure 1,

Figure 3 is a sectional plan on line III—III of 35 Figure 1, and

Figures 4, 5 and 6 are fragmentary views, to 40 an enlarged scale, showing relative positions assumed by the component parts of the appliance during a cap securing operation.

In the embodiment illustrated in the drawing, the housing comprises a vertically disposed hollow cylindrical shell 1 having a stepped bore, the lower part 2 of which is inwardly and upwardly tapered toward an upwardly facing shelf 3 provided about midway along the length of the shell bore. Concentrically within the cylindrical shell is the lower part of a vertically displaceable 45 slideable pressure plunger 4, the underface of which is adapted to be contacted by the rim of an ascending bottle 5, a preformed cap 6 with a deformable skirt 7 having been placed on said bottle rim. The upper end of the plunger 4 is guided within a bushed boss 8 provided in the crown of a dome-like cover 9 which is screw-threaded onto the upper part of the cylindrical shell 1. Within the annular space formed 50 between the pressure plunger 4 and encircling shell

1 a lateral pressure applying means is provided in the form of a contractile ring assembly 10. This contractile ring assembly consists of a number of circumferentially-spaced arcuate substantially rigid metal sections 11, 11, each section 11 having intermediately of the length of its inner face an inwardly directed rib 12. The ribs 12, 12 of the plurality of sections 11, 11 form fulcrums about which the sections 11, 11 can rock, as described later. The fulcrum ribs 12, 12 of the sections 11, 11 enter an annular groove 13 formed in the periphery of the pressure plunger 4, the width of said groove 13 being greater than the thickness of the ribs 12, 12 so that the plunger 4 can partake of a prearranged axial movement before axial movement is transmitted to the ring sections 11, 11. Each ring section 11 is provided on its exterior surface with two outwardly extending ribs 14, 15, one, that is rib 14, near the bottom end of the section 11, being adapted to be maintained in contact with the tapered bore 2 of the shell 1. The other rib 15, which is provided near the top end of the section 11 normally rests upon the shelf 3 in the encircling shell 1. A coiled compression spring 16 encircles the guided shank 17 of the pressure plunger 4, and is interposed between a collar 18 or the like on the plunger shank 17 and the end of the boss 8 (or of the boss bush) in the crown of the cover 9, so as normally to urge the plunger 4 to the bottom of its stroke. Just below the level of the underface of the plunger 4 a round rubber cap-closure ring 19 is accommodated within an internal groove 20 provided in the assembly of ring sections 11, 11. When the components of the appliance are in their normal inoperative positions the upper outer ribs 15, 15 on the ring sections 11, 11 constitute fulcrums upon which the sections 11, 11 are supported by the shelf 3 in the cylindrical shell 1 and a garter spring 21 encircling the upper ends of the sections or, as shown, of a number of rods 22 extending upwards from said sections 11, 11, causes them to be rocked about the upper outer ribs 15, 15 so as to maintain the lower outer ribs 14, 14 of the ring sections 11, 11 in contact with the tapered bore 2 of the shell 1.

When a bottle 5 carrying a loose skirted cap 6 is moved upwards through the open bottom of the shell 1 it contacts the pressure plunger 4 and lifts it a prearranged distance before the bottom of the groove 13 in the plunger 4 contacts with the internal ribs 12, 12 of the stationary ring sections 11, 11 by which time the lower part of the cap skirt 7 lies opposite the rubber ring 19 held with the lower part of the ring assembly 10. Continued upward movement of the cap-bearing bottle 5 causes the pressure plunger 4 to lift the ring sections 11, 11 from off the shelf 3 in the cylindrical shell 1, with the result that the narrowing tapered bore 2 of the shell 1, by pressing on the lower outer ribs 14, 14 of the ring sections 11, 11, rocks said sections 11, 11 in the plunger groove 13 on the fulcrum-forming internal ribs 12, 12 of the ring sections 11, 11, thereby forcing the rubber closure ring 19 in the lower part of the ring assembly 10 onto the skirt 7 of the cap 6 so as to deform it and thus secure the cap 6 on the bottle 5. Three successive stages of the cap securing operation are illustrated in Figures 4, 5 and 6 respectively.

The ascending movements of the bottle 5 and loose cap 6 (and with them the pressure plunger 4) are effected against the resistance of the plunger spring 16, so that when the capped

bottle 5 is lowered the plunger 4 follows and the plunger spring 16, aided by the garter spring 21 of the ring sections 11, 11, resets the components in their normal inoperative position.

5 Among other advantages of this construction of cap securing appliance may be named these, that the rubber closure ring 19 can be removed and replaced without stripping the appliance or disarranging any of the other components, and that as the rubber closure ring 19 is set so as to be slightly above the level of a cap-skirt receiving groove 23 in the bottle neck at the commencement of the capping operation, the rubber ring 19, during the capping operation, flows downwards into said bottle neck groove 23, thus giving a smooth stroking action to the skirt of the preformed cap. An important feature of this rubber closure ring 19 is in its round section, which gives concentrated loading at the point required. Furthermore, only the minimum of force is required for a perfect closure. Another advantage is that a bottle cannot be held up in the appliance as the bottle top only partially enters the closure ring.

I claim:

25 1. A bottle cap closing appliance of the type specified comprising, in combination, a housing having an inwardly and upwardly tapering bore and a shelf above said tapered bore; a pressure plunger mounted centrally within said housing for vertical movement and having a downwardly directed head; first spring means biasing the plunger head toward the lower and larger part of the tapered housing bore; a contractile ring assembly interposed between said tapered housing bore and said pressure plunger and constituted by a plurality of circumferentially arranged arcuate sections, each of said arcuate sections having a lower external projection for co-operating with said tapered housing bore, an upper external projection for co-operating in fulcrum manner with said housing shelf and with an internal projection disposed intermediately of said external projections for co-operating with the upper side of the plunger head; a continuous elastic ring supported within the lower ends of said ring sections below the plunger head, and second spring means applying radially inward pressure to the ring sections to maintain the lower external projections of said ring sections in contact with the tapered housing bore, the arrangement being such that upward displacement of the plunger by pressure applied axially through a bottle bearing a loose cap causes the tapered housing bore first to swing said ring sections radially inwardly upon the upper outer projections resting on the upwardly facing housing shelf and then to lift the ring sections from the shelf so that thereafter the ring sections are rockably supported by the internal projections on the upper face of the plunger head.

60 2. A bottle cap closing appliance as claimed in claim 1, wherein the internal projections of the arcuate sections engage a common external groove on the pressure plunger, the width of said groove being such that the pressure plunger is capable of an axial receding movement before the said plunger causes the arcuate sections to rock inwardly.

THOMAS LESLIE GOLDSMITH.
